CLAIM

The ornamental design for a personal viewing device, as shown and described.

DESCRIPTION

FIG. 1 is a left perspective view of a personal viewing device showing Applicant's design;

FIG. 2 is a frontal view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating portions of the personal viewing device that form no part of the claimed design.

1 Claim, 5 Drawing Sheets
